LEE S. CHADWICK, OF SHAKER HEIGHTS VILLAGE, OHIO, ASSIGNOR TO PERFECTION STOVE COMPANY, OF CLEVELAND, OHIO, A CORPORATION OF OHIO.

THERMOSTATIC OIL BURNER.

Application filed September 26, 1923. Serial No. 664,852.

My present invention relates to liquid fuel burners and more particularly to means for automatically extinguishing the flame or reducing the size of the flame when the 5 burner parts become overheated. It involves a thermostat which is responsive to the temperature of the metallic parts of the burner or to the temperature of the oil in the immediate vicinity of the burner parts, and which 10 is practically unaffected by the temperature of the flame. The subject matter of the present case is thus distinguished from that of my earlier application Serial No. 488,107, filed February 26, 1921, wherein is disclosed 15 thermostatic means subjected to the heat of the flame for reducing the size of the flame, as by lowering the wick, in the event the temperature of the flame becomes excessive.

The objects of my present invention are 20 to provide means responsive to the temperature of the metallic parts of a liquid fuel burner, either by radiation of heat therefrom or metallic continuity therewith, which will act automatically to reduce the size of the 25 flame should the temperature of such parts become excessively high; to provide means responsive to the temperature of the liquid fuel sustained in proximity to the metallic parts of a liquid fuel burner which will act 30 automatically to reduce the size of the flame should the temperature of the liquid fuel become excessively high; to provide means, pursuant to either of the foregoing objects, which acts to shut off the supply of liquid 35 fuel to the burner; and to provide means, such as any of the foregoing, which is adjustable to cause it to operate at different degrees of temperature.

Further aims are to provide a device 40 through which the several foregoing objects are attained in a highly efficient manner and which is compact, simple and inexpensive of construction, is very durable, and is practically immune from disorder.

45 Embodiments serving to illustrate my invention are shown in the accompanying drawing and while I shall proceed to describe the present embodiments in detail it will be understood that I do not limit myself to the structural features thereof further than is required by the terms of the 50 claims annexed hereto.

In the drawings, Fig. 1 is a vertical section through a liquid fuel burner embodying one

form of my invention; Fig. 2 is a horizontal 50 section on the line 2-2 of Fig. 1; Fig. 3 is a sectional side elevation of a liquid fuel burner equipped with a modification of the invention; Fig. 4 is a fragmentary sectional view of a burner incorporating a further 60 modification; Fig. 5 is a sectional detail showing an adjustment which is applicable to either of the forms shown in Figs. 3 or 4; Fig. 6 is a vertical section through a burner embodying another modification of the invention; and Fig. 7 is a section on the line 7-7 of Fig. 6.

I have elected to show my invention associated with a wick burner of the tubular type wherein the inner and outer wick tubes 70 are designated 1 and 2, respectively, and are joined together at their lower ends by an annular wall 3 which, in the present instance, is an integral part of the outer wick tube. Within the annular reservoir 4, enclosed by the tubes 1 and 2, is a cylindrical wick 5 equipped with the usual carrier 6. In burners of the type illustrated there are pinions 7 which engage the carrier 6 to raise and lower the wick when a spindle 8, to 80 which the pinions are secured, is rotated by a handle 9 applied to its outer end. The spindle and pinions are enclosed within a sleeve 10 and casing 11, respectively.

The foregoing parts are common to all 85 forms of the invention illustrated in the drawings and will be designated by like reference characters throughout the several views.

In the form shown in Figs. 1 and 2 a valve 90 casing 15 is supported within the lower end of the inner wick tube through lateral extensions 16 which are flanged at their outer ends and suitably connected to the wick tube. A boss 17 which depends from the 95 valve casing is threaded into the vertical branch of a T 18 through which sections of a fuel supply pipe 19 are connected together. The boss 17 and extensions 16 have bores 100 through which communication is established between the supply pipe, valve casing, and reservoir 4. A valve seat 20 surrounds the inner end of the bore of boss 17 and a valve 21 is arranged for cooperation therewith. The valve is carried by a diaphragm 25 105 which has its periphery clamped between the flanged upper end of the valve casing and a ring 26 secured thereto by screws 27. The

joint between the diaphragm and the valve casing is rendered liquid-tight by solder or other suitable means.

A thermostat 28, comprising a bellows containing a suitable fluid which is very susceptible to temperature changes and expands when heated causing the bellows to elongate, is interposed between the diaphragm and the central portion of an inverted U-shaped yoke 10 that rises from the ring 26. The connection between the thermostat and the yoke is preferably made adjustable so that, through the thermostat, the valve may be adjusted toward and from its seat. Thus the valve may 15 be caused to close at different temperatures. The adjustable connection may be effected through a nut 29 that is rotatably mounted in the yoke and threaded on a stud 30 that extends from the thermostat.

20 When the burner parts become unduly heated, especially the inner wick tube 1 which is more susceptible to an overheated condition than the other parts, the heat is radiated to the thermostat 28, and 25 in part conducted thereto through the metal connections between it and the burner, causing the fluid in the thermostat to expand and the bellows to elongate as above explained, thereby to depress the valve 21 against the 30 seat 20. This shuts off the supply of oil to the reservoir 4 and the flame gradually diminishes until the temperature of the parts falls sufficiently to cause the thermostat to contract or shorten and lift the valve.

35 Of course, the adjustment may be such as will cause the flame to be extinguished and require its being relighted after the parts cool.

The form of the invention illustrated in 40 Fig. 3 will next be described.

Secured to one side of the outer wick tube 2 adjacent its lower end is an elbow fitting 35 through which communication is established between the reservoir 4 of the burner 45 and a fuel supply pipe 36, the elbow being shown as bound against a seat 37 on the pipe by the usual clamp 38.

The elbow fitting 35 is provided with an internally threaded boss 40 into which the 50 neck 41 of a casing 42 is adapted to be screwed, and the joint between the neck and boss may be rendered liquid tight by a gasket 43 of relatively hard material, or, in lieu thereof, the joint may be soldered or similarly sealed. To the end wall 45 of the casing 42 is secured one end of a thermostat 46, and the other end of the thermostat carries a valve member 47 in the form of a rod, which is guided within the neck of the casing 60 and has its end shaped for cooperation with a seat 48 that is formed in the passageway of the elbow fitting 35 between the supply pipe 36 and the reservoir 4. When the thermostat 46 is expanded by a rise in temperature, it advances the valve 47 toward the

seat 48. Communication between the reservoir 4 and the casing 42 is established through grooves 47^a in the valve member 47.

Attention is directed to the facts that metallic connection is uninterrupted between 70 the burner parts and the thermostat 46; and that said thermostat is submerged within a body of liquid fuel situated in close proximity to and in continuity with that in the reservoir 4. Accordingly, should the burner 75 parts, as the tubes 1 and 2, especially the former, become overheated through any cause and create a dangerous condition, the temperature of said parts will be transmitted rapidly to the thermostat 46 and cause it to 80 expand and engage the valve 47 with the seat 48 and shut off the supply of liquid fuel to the reservoir 4 thereby to effect in a comparatively short time, a diminishing of the flame through lack of fuel. Whether the 85 flame is reduced or wholly extinguished is dependent upon the sensitiveness of the thermostat and upon the adjustment of the valve with respect to the valve seat. In case the thermostat is very sensitive and the adjustment proper for the attainment of such a result, the valve will be withdrawn from the seat after the flame has been reduced and the temperature of the burner parts consequently lowered, allowing a fresh supply of 90 fuel to flow into the reservoir. While I have mentioned the fact that the thermostat is in metallic connection with the burner parts so that the temperature of said parts will be quickly transmitted to said element, I wish 100 also to make clear that the prompt action of the thermostat is further assured by the fact that the element is submerged within a body of liquid fuel that is in close proximity to that contained within the reservoir 4. Consequently the overheated condition of the liquid fuel within the reservoir 4 will be effective in causing the thermostat to act to shut off the supply of fuel.

The construction and operation of the 110 form of the invention illustrated in Fig. 4 will be readily apparent from what has been said of the form shown in Fig. 3. The marked difference between the two forms is in the location of the thermostat. In Fig. 4 it is shown, as in the first instance, located inside the burner and consequently under the more direct influence of an overheated condition of the interior of the burner where overheating develops the quickest and is least 115 affected by the surrounding air.

The same reference characters are used to designate the identical parts in Figs. 3, 4 and 5.

Pointing out the structural differences between the two forms shown in Figs. 3 and 4, the elbow fitting 35, shown in Fig. 4, has an inwardly directed portion 40^a that is extended through aligning holes in the inner and outer wick tubes 1 and 2 and is externally 130

threaded for the application of the internally threaded neck 41^a of the thermostat casing 42.

While the adjustment illustrated in Fig. 5 may be incorporated in either of the foregoing forms, I have shown it in connection with the form illustrated in Fig. 3. Here, the neck 41^b of the casing 42 is threaded into the portion 40^b of the elbow fitting 35, 10 and by turning the casing 42 it may be adjusted in and out to advance the valve 47 nearer the seat 48 or to withdraw it further therefrom. By this adjustment the thermostat may be caused to act to shut off the 15 flow of fuel at different degrees of temperature.

In Figs. 6 and 7 I have shown a very simple, yet thoroughly efficient embodiment of the invention wherein a thermostat 50 is 20 located inside the lower portion of the burner with its axis disposed transversely thereof, one end of the thermostat being secured to a reinforcing plate 51 that is applied to one side of the inner wick tube 1, while the 25 other end is adjustably connected through reversely threaded stems 52 and 53, and a sleeve nut 54, to a diametrically opposite portion 55 of the inner wick tube. The portion 55, which is shown as flat, constitutes 30 a valve for cooperation with the inner end of a tubular extension 57 of an elbow fitting 58 through which the wick space of the burner communicates with the supply pipe 59. A clamp 60 binds the elbow fitting 58 35 to a seat 61 on the supply pipe.

When the thermostat is elongated through a rise in temperature of the surrounding burner parts, it forces the portion 55 of the inner wick tube against the end of the extension 57 of the elbow fitting thereby to 40 shut off the flow of oil to the reservoir or wick space 4 until the thermostat subsequently shortens. By means of the nut 54 the mechanism may be adjusted to act at 45 different temperatures.

In Fig. 1 there is shown, in dot-and-dash lines, associated with the burner the usual air controlling member or flame spreader 65, the flue or drum 66, and the drum supporting collar 67.

With respect to the various embodiments it is evident that the temperature of the thermostat is maintained substantially equal to that of the burner tubes or adjacent burner parts through any one of the 55 following causes, to-wit: radiation of heat from the burner parts; conduction of heat through the metal connections between the burner and the thermostat; or conduction of heat through the liquid fuel.

It will be readily apparent to those familiar with liquid fuel burners of both the wick and wickless types that my present 65 invention is applicable to the latter type, as well as the former in connection with

which it is herein disclosed. Therefore it is to be understood that I do not limit myself to the type of burner shown. By way of explanation it may also be said that where the expression "excessively high" or 70 its equivalent is used in the claims to modify "temperature" it is intended to mean a temperature above what is practical and safe.

Having thus described my invention, what 75 I claim is:—

1. In combination with a liquid fuel burner of the tubular type, thermostatic means situated within and surrounded by the burner tubes so as to receive the radiant 80 heat therefrom, and means through which said thermostatic means acts to reduce the size of the flame when the temperature of the burner parts becomes excessively high. 85

2. In combination with a liquid fuel burner, a fuel supply, communicative connections between said fuel supply and the burner, a valve in said connections, said valve comprising a seat and a valve member for cooperation therewith, and thermostatic means so situated with respect to the burner as to be affected by the temperature of the burner parts, said means acting to force the valve member against the seat when the thermostatic means is caused to 95 operate by a rise in temperature of the burner parts to an excessively high degree. 90

3. In combination with a liquid fuel burner of the tubular type, a valve casing situated within the lower end of the inner wick 100 tube, a liquid fuel supply pipe, said valve casing having communicative connection with both the wick space of the burner and the fuel supply pipe, a valve member within said casing adapted, when actuated, to 105 shut off communication between the supply pipe and the valve casing, a diaphragm extending across one side of the valve casing and to which the valve is connected, an abutment spaced above and fixed with respect to 110 the valve casing, and a thermostatic element interposed between said abutment and the diaphragm. 115

4. In combination with a liquid fuel burner of the tubular type, an open-top valve 120 casing situated within the lower portion of the inner wick tube and connected thereto by a tubular lateral extension thereby to establish communication between the interior of the valve casing and the oil reservoir between the wick tubes, a liquid fuel supply pipe, connections between said supply pipe and the valve casing, a valve for shutting off such communication, a diaphragm closing the open side of the valve 125 casing and having operative connection with the valve, an abutment spaced above and fixed with respect to the valve casing, and a thermostatic element interposed between the diaphragm and said abutment. 130

5. In combination with a liquid fuel burner of the tubular type, an open top valve casing situated within the lower portion of the inner wick tube and connected thereto by a tubular lateral extension thereby to establish communication between the interior of the valve casing and the oil reservoir between the wick tubes, a liquid fuel supply pipe, connections between said supply pipe and the valve casing, a valve for shutting off such communication, a diaphragm closing the open side of the valve casing and having operative connection with the valve, an abutment spaced above and fixed with respect to the valve casing, a thermostatic element interposed between the diaphragm and said abutment, and means for adjusting the thermostatic element toward and from the abutment.
- 10 6. In combination with a liquid fuel burner of the tubular type, a valve casing situated within the lower end of the inner wick tube, a liquid fuel supply pipe, said valve casing having communicative connection with both the wick space of the burner and the fuel supply pipe, a valve member within said casing adapted, when actuated, to shut off communication between the supply pipe and the valve casing, a diaphragm extending across one side of the valve casing and to which the valve is connected, an abutment spaced above and fixed with respect to the valve casing, a thermostatic element interposed between said abutment and the diaphragm, and means for adjusting the valve.
- 15 7. In combination with a liquid fuel burner of the tubular type, an open-top valve casing situated within the lower end of the inner wick tube and connected thereto through lateral branches having bores between the interior of the casing and the oil reservoir of the burner, the valve casing having a hollow depending boss, a liquid fuel supply pipe to which said boss is communicatively connected, the boss incorporating a valve seat, a diaphragm extending across and closing the open top of the casing, a valve supported by said diaphragm in operative relation to the valve seat, a yoke rising from the valve casing, and a thermostatic element interposed between the dia-
- phragm and an opposed portion of the yoke.
8. In combination with a liquid fuel burner of the tubular type, an open-top valve casing situated within the lower end of the inner wick tube and connected thereto through a lateral branch having a bore through which communication is established between the interior of the casing and the oil reservoir of the burner, the valve casing having a hollow depending boss, a liquid fuel supply pipe to which said boss is communicatively connected, the boss incorporating a valve seat, a diaphragm closing the open top of the casing, a valve supported by said diaphragm in operative relation to the valve seat, an abutment spaced above and fixed with respect to the valve casing, a thermostatic element interposed between the diaphragm and said abutment, and adjustable connections between the thermostatic element and the abutment.
- 20 9. In combination with a liquid fuel burner of the tubular type, a valve casing situated adjacent the lower end of the inner wick tube, a liquid fuel supply pipe, said valve casing having communicative connection with both the wick space of the burner and the fuel feed supply pipe, a valve member within said casing adapted, when actuated, to shut off communication between the supply pipe and the wick space of the burner, and a thermostat associated with said valve casing and to which the valve member is connected.
- 25 10. In combination with a liquid fuel burner comprising inner and outer wick tubes enclosing between them an annular fuel reservoir into which the wick extends, a liquid fuel supply pipe, a casing enclosing a chamber, connections establishing communication between said reservoir, supply pipe and chamber, a valve for shutting off communication between the supply pipe and reservoir, and thermostatic means associated with said chamber and acting to close the valve when the heat generated by the burner and to which the thermostatic means is subjected becomes excessively high.
- 30 95 In testimony whereof, I hereunto affix my signature.

LEE S. CHADWICK.
